[57] **CLAIM**

The ornamental design for a foldable traveling jewelry holder, as shown and described.

DESCRIPTION

FIG. 1 is a front perspective view of a foldable traveling jewelry holder showing my new design;

FIG. 2 is a left side elevational view thereof;

FIG. 3 is a right side elevational view thereof;

FIG. 4 is a top plan view thereof;

FIG. 5 is a bottom plan view thereof; and

FIG. 6 is a perspective view in extended position with an intermediate hold-down sheet in a partially raised position.
